DESIGN FOR A DISPLAY CASE

Julian G. Everett, Dobbs Ferry, and Charles J. Clark, Port Washington, N. Y., assignors to American Chicle Co., Long Island City, N. Y., a corporation of New Jersey

Application May 28, 1942, Serial No. 107,044

Term of patent 7 years

To all whom it may concern:

Be it known that we, Julian G. Everett and Charles J. Clark, citizens of the United States, residing, respectively, in Dobbs Ferry, county of Westchester, and Port Washington, county of Nassau, both in the State of New York, have invented a new, original, and ornamental Design for a Display Case, of which the following is a specification, reference being had to the accompanying drawing, forming part thereof.

We claim:

The ornamental design for a display case, as shown.

JULIAN G. EVERETT.
CHARLES J. CLARK.
